UNITED STATES PATENT OFFICE.

JOHN S. DAVIS, OF TOLEDO, OHIO, ASSIGNOR TO THE TOLEDO MOWER AND REAPER COMPANY, OF SAME PLACE.

GRAIN-BINDING HARVESTER.

SPECIFICATION forming part of Letters Patent No. 275,330, dated April 3, 1883.

Application filed September 1, 1882. (Model.)

To all whom it may concern:

Be it known that I, JOHN S. DAVIS, of Toledo, in the county of Lucas and State of Ohio, have invented certain new and useful Improvements in Grain-Binding Harvesters, of which the following is a specification.

My invention relates to improvements—to be hereinafter distinctly claimed—applicable to grain-binding harvesters of the class usually designated "platform-binders"—that is, those in which the grain is delivered in or nearly in horizontal paths from the grain-platforms to low-down receptacles, to be bound on or substantially on the levels of the platforms and in rear of the main frames of the harvesters.

The accompanying drawings represent a suitable application of my improvements. Some of these improvements may, however, be used without the others and in machines differing in some respects from that shown and hereinafter particularly described, and the details of construction may be modified in various ways without departing from the principle of my invention.

Figure 1 is a plan or top view, some parts being omitted and other parts broken away or in section, especially designed to show features of the main frame and binder-frame and the manner of connecting the binder-frame, platform, cutting apparatus, &c., with and supporting them by the main frame. Fig. 2 is a side elevation representing features shown by Fig. 1, parts being broken away. Fig. 3 is a plan or top view, showing the binder-frame, the mechanism supported thereby, and comprising devices for gaveling, compressing, binding, and discharging the grain, also showing the inner ends of the platform, finger-beam, and grain-carrier, the cut-off, and gearing for actuating various devices, parts being broken away or in section, and the shaft and gear-wheel by way of which motion is communicated to said actuating-gearing being omitted. Fig. 4 is a side elevation representing features shown by Fig. 3, parts being broken away or in section, and also showing the sprocket-wheel and shaft and the bevel-gear by which motion is imparted to the actuating-gearing of the carrier, the binding mechanism, &c. Fig. 5 is a front elevation representing the binder-gearing supported by the

gear-plate portion of the binder-frame, the binder-arm shaft, the manner of connecting the binder-frame and finger-beam, the rake-post stand or support, and other parts. Fig. 6 is a view partly in rear elevation and partly in vertical section on the line 6 6 of Figs. 3 and 4, showing the binder-frame and mechanism supported thereby, and a portion of the platform, and in part the mechanism supported by it and by the finger-beam, including the rotary swinging butt-guide and the reel-post and shaft, and mechanism for actuating these devices. Fig. 7 is a view in elevation and section similar to Fig. 6, except that many parts there shown are omitted, and the devices illustrated are represented in the positions occupied after a gavel has been accumulated and compressed and has the band about it, instead of being in the positions for accumulating a bundle, as in the preceding figure. Fig. 8 is a view partly in front elevation and partly in section on the lines 8 8 of Figs. 3 and 4. Fig. 9 is a view partly in elevation and partly in section on the lines 9 9 of Figs. 1 and 6. Fig. 10 shows a vertical central section of the butt-guide, and Fig. 11 a top view thereof. Fig. 12 is a plan view, showing portions of the platform, the carrier, and the carrier supporting and adjusting mechanism, the belts of the carrier being partly broken away; Fig. 13, a view partly in rear elevation and partly in section on the line 13 13 of Fig. 12. Fig. 14 is a side view of a ratchet-toothed sprocket-wheel which is loosely mounted on the main axle, the pawl-carrier or dog-plate by which said wheel is clutched with the axle being removed; and Fig. 15, a view of the pawl-plate, showing its inner face and the spring-actuated pawl. Fig. 16 is a view partly in elevation and partly in section on the line 16 16 of Fig. 1, showing a portion of the lever and the detent devices by which to adjust the main frame to elevate or lower the binder-frame, platform, &c. Fig. 17 is a view partly in elevation and partly in section on the line 17 17 of Fig. 1, showing the segment-gear, pinion, and rock-shaft by which the main frame is connected with its vertically-adjusting lever, and also showing, in part, the lever and detent devices for tilting the platform, &c., and securing the parts in their adjusted positions. Fig. 18 is a

plan view, showing portions of the main frame, tongue, diagonal bracing-connection between the tongue and frame and seat-supporting cross-piece, with the mechanism for tilting the 5 finger-beam, &c., and for rocking the main frame to raise and lower the finger-beam, binder-frame, &c. Fig. 19 is a section on the line 19 19 of Fig. 8, showing one part of a casing for the shaft of a rotating packer and two of 10 a series of shorter sleeves, also incasing the packer-shaft, and having ears to which to attach cleaners or strippers for clearing the grain from the packer-arms. Fig. 20 is a plan view, showing detail of clutch and clutch-shifting mechanism by which to control the actuations of the 15 cut-off and grain-carrier; Fig. 21, a section on the line 21 21 of Fig. 20; Fig. 22, a front elevation of the clutch-shipper or vibrating lever actuated from the rock-shaft of the cut-off to 20 throw the carrier into and out of operation; Fig. 23, an end view of the cut-off shaft and its attachments; and Fig. 24, a top view of the outer end of the cut-off shaft, showing its crank and shipper-actuating cam and a portion of 25 the pitman by which the shaft is rocked. Fig. 25 is a plan view of a two-part or doubly-toothed idle-pinion which drives the packer-shaft, gear-wheel, and is actuated by the driving-gear of the binding-gearing. Fig. 26 is a 30 plan view of a pinion which is rotated by the packer-gear and intermittently drives a large gear-wheel—termed the “binder-gear”—by which the knotter, binder-arm, &c., of the binding mechanism are actuated. Fig. 27 is a plan 35 view of a pinion which is intermittently actuated by the binder gear-wheel to operate the cut-off. Fig. 28 is a view of the outer or front side of the binder-gear; Fig. 29, a top view of the binder-gear, and Fig. 30 a view of the inner or 40 rear side of the binder-gear, with the pinion of the knotter-shaft represented in dotted lines. Fig. 31 is a plan view, showing details of the knotting mechanism and manner of supporting 45 the knotter-box, the top of the box being removed. Fig. 32 is a plan view, showing the knotter-box without the cover and the knotting mechanism, and with mechanism by which to retain the grain in the receptacle as accumulating, compress it while being bound, dog the 50 binder-arm while a knot is being tied, and discharge the bound bundles. Fig. 33 is a view in elevation, as seen from the outer or stubble side of the machine, of the knotter-box, the knotter-pinion, the retainer, compressor, and dis- 55 charger, and the mechanism for dogging and releasing the binder-arm and the compressor, the binder-gear being shown in section and the knotter-head or tying-bill omitted. Fig. 60 34 is an end view, showing the knotter-pinion, the rock-shaft and attachments thereof by which the device for retaining, compressing, and discharging the bundle is controlled, and the rock-shaft and its attachments for dogging and releasing both the binder-arm and the de- 65 vice by which the gavel is compressed, &c. Fig. 35 is a detail view in elevation, showing the binder-arm as in its lowermost or locked

position, a compressor which is actuated thereby to compact the bundle from above, and the combined retaining, compressing, and discharging device, the dotted lines showing said device in the position which it is caused to assume during the looping of the cord and tying of the knot. Fig. 36 shows a section of a tubular stud or thimble and a longitudinal view of 70 a bolt, with its nuts and washers, used with said thimble to secure the binder-gear in place, similar devices being employed to mount other members of the binder-gearing upon their supporting-plate. Fig. 37 shows two views of the 75 box for mounting the gear end of the packer-shaft upon the gear-supporting plate. 80

In some respects features shown in connection with my present invention are the same as or more or less nearly resemble devices and combinations of mechanism shown and described in connection with or as constituting the subjects-matter of sundry prior inventions of mine, including improvements set forth in United States Letters Patent No. 260,668, dated July 90 4, 1882, for improvements in grain-binding mechanism, No. 252,081, dated January 10, 1882, for improvements in grain-carriers, No. 267,064, of November 7, 1882, for improvements in clutches, and No. 271,430, of January 30, 1883, for improvements in harvesters. United States Letters Patent numbered 261,590 and 261,591, for improvements in grain-binders, both dated July 25, 1882, also show inventions made by me prior to the date at which 100 the improvements hereinafter claimed were made, parts of which inventions may be applied to suitable machines in connection with my present improvements, or some of them. 105

In order to provide a binder-harvester which shall be very light and of easy draft as compared with the usually-constructed weighty and unwieldy machines, and at the same time be strong and durable, I provide, as in turn to be fully explained, a main frame and an auxiliary or binder frame and a grain-platform connected therewith and with each other, and so construct or organize these parts, support them upon the main axle, and mount upon the main frame and binder-frame the mechanism 110 carried by them that, in connection with the weight of the driver, there will be sufficient weight concentrated at the outer or stubble side of the machine and in front and in rear of the main axle to relieve the grain-wheel of 115 injurious downward pressure and to properly balance the machine upon its main support or drive wheel. 120

The driving and main supporting wheel A is fastened to its axle A', and is surrounded by a main frame, B, which, as shown in Figs. 1 and 2, is suspended from the main axle A' by brackets or down-hangers B' B', provided with suitable bearings at their upper ends, and at their lower ends firmly bolted to the frame, 125 so that the frame may be rocked about the axle as though made in one piece with its suspending-brackets. The main frame, it should be noticed, extends along close to the drive- 130

wheel at the inner or grain side thereof, and at the opposite side of the wheel the frame is at a distance from it such as to bring the greater portion of its weight outside of the center of the drive-wheel's tread, and so as to admit of locating the cutter-actuating gearing inside the frame and at the outer side of the wheel. By mounting the main frame and arranging the gearing in this way they aid in counterbalancing the weight of parts inside of the drive-wheel, and as the gearing is located in advance of the axle its weight also assists in counterbalancing the weight of parts in rear of the axle. The main frame has two forks or arms, b , at its rear, preferably provided by forming the frame of a flat wrought-iron bar bent into a yoke or U shape, and this yoke-shaped bar, near the rear or open end, being firmly braced by a tie-piece or cross-bar, B^2 , bolted or riveted at its bent-ends to the opposite members of the yoke, as plainly shown in Fig. 1. The cutter-driving crank-shaft C is outside the drive-wheel and inside the main frame, and is mounted at or near its rear end in a bearing, b' , bolted to this cross-bar portion of the main frame. At its opposite end the crank-shaft is mounted in a bearing formed in a hollow gear-block or casing-support, C' , bolted by a flange to the main frame at its outer side. A bevel-pinion, c , fast with the crank-shaft, is actuated by a bevel-gear, C^2 , which is fitted loosely on a shaft, c' , mounted in the gear-block, and rotated by a pinion engaging the internal gear of the driving-wheel. Internal ratchet-teeth on the gear C^2 are acted upon by a pawl on the inner face of a plate, c^2 , fixed to the shaft c' . The pawl is so formed, mounted, and acted upon by a spring that it can be caused to keep the bevel-gear locked to its shaft, except when the machine is backed, or be set to allow of the rotation of the shaft independently of the gear, as will further on be understood with the aid of Figs. 14 and 15 and the description of the connection of the axle and its sprocket-wheel.

A tongue, A^2 , is jointed at its heel to the main frame, close to the inner front corner thereof, in suitable way, as by means of a pivot-bolt, a , and its thimble or inclosing-sleeve and nuts and washers. This bolt a also serves as a means of connecting the forward end of a diagonal brace or draw bar, C^3 , with the front end of the main frame. This draw-bar is also supported by being suspended from the axle by a hanging bracket, a' , similar to the before-described main-frame brackets B^1 , B^1' . This bracket a' fits at its upper end, by its box or bearing sleeve, on the inner end of the axle A^1 , and its lower end has the draw-bar bolted to it. A cross-bar and seat-supporting piece, A^3 , is bolted at one end to the under side of the tongue and slightly in advance of the main frame, outside or beyond which it extends and supports the driver's seat A^4 well outside of the main frame, and in advance of the axle. A bent brace-bar, B^3 , connects the tongue with the main frame close to its outer front

corner, and also serves as a support for the cross-piece A^3 . The rear end of the brace B^3 is pivotally connected at a^2 with the main frame diametrically opposite to or directly in line with the point of pivotal attachment of the tongue to the inner front corner of the frame. From the pivot-bolt a^2 the brace extends straight forward to the front edge of the cross-piece A^3 , which rests beneath it, and is rigidly attached to it by an angular casting or bracket, B^4 . Bolts passing through the vertical and base portions of the bracket and through the brace and cross-piece, together with a flange or side ledge, b^3 , overlapping the brace, firmly connect the parts together. The brace B^3 is bent at the front edge of the cross-piece A^3 and extends diagonally forward to the tongue, to which it is firmly connected by a bolt, b^2 , at its front end.

A rock-shaft, C^4 , is mounted above and extends parallel with the tongue-attached cross-piece A^3 . It is provided with a rocking lever, C^5 , and detent devices, and acts by connecting mechanism upon the main frame, so as to rock the frame about the axle A^1 and raise or lower the finger-beam, &c., attached to the rear of the frame. This connecting mechanism, as shown, consists of a pinion, c^3 , fast on the rock-shaft, and a sector-gear, c^4 , cast with a flanged clip or socket-piece to embrace the main frame, to the front cross portion of which it is firmly connected by bolts. The rock-shaft is suitably supported by being mounted at one end in a bearing in the bracket-casting B^4 , and at its opposite end in a bearing in another bracket, A^5 , secured to the cross-piece and to the tongue by bolts passing through its base and through its vertical portion. This bracket terminates at top in a detent-rack, a^3 , with which engages a spring-actuated detent, a^4 , of well-known construction, of a lever, A^6 , to which is connected a link, a^5 , for tilting the finger-beam, &c., as further on made apparent. This tilting-lever rocks loosely on the shaft C^4 .

The lifting and lowering lever C^5 is mounted loosely on the rock-shaft C^4 , and is provided with a locking dog or pawl, b^4 , which is pivoted to the lever and controlled by a link and handle, b^5 . This lever-pawl engages a detent-wheel, B^6 , fast on the rock-shaft, so that this shaft may be turned by the driver while in his seat. A detent-holding dog, b^6 , is pivotally supported by the casting B^4 , and provided with a crank, b^7 , by which it can be operated by the driver's foot to release its hold on the detent-wheel B^6 when the rock-shaft is to be actuated by the lever C^5 and pawl b^4 in an obvious way.

A cranked rock-shaft, D , is mounted in advance of the cross-piece A^3 in bearings formed by brackets d , d' , respectively bolted to the tongue and to the brace B^3 . A lever, D' , serves to rock the shaft D , and means are provided by which this lever is made to hold the shaft in any desired position of adjustment. A link-rod, D^2 , serves to connect the crank d^2 of the rock-shaft with a "butt-guide" or device

for evening the grain on the platform, so as to adjust this device, as further on to be described, by actuating the rock-shaft. The lever D' is in this instance adapted to turn with the rock-shaft, while capable of swaying slightly in the direction of the length of this shaft or toward and away from a detent-plate composed of lugs projecting from a plate, D^3 , formed with the bracket d' . A spring, d^3 , secured to the lever and acting on the detent-plate, serves to hold the lever normally in one of the spaces formed between two of the lugs, while allowing the lever to be disengaged for adjustment by the driver, who first pushes the upper end of the lever toward the tongue, and after moving it allows the spring to return it to its locked position against the detent-plate. Any suitable form of detent mechanism may be employed instead of that just described.

A light supplemental binder-frame or skeleton support for the binding mechanism has rigid connection with a finger-beam, D^4 , and grain-platform D^5 , and with them is pivotally connected to and supported by the main frame B , and partakes of their rising and lowering and rocking or tilting movements. This binder-frame, as shown, is composed mainly of two sills, E E' , the heel end or prolongation of the angle-iron finger-beam and the corresponding prolongation of a rear piece or back-beam, D^6 , of the platform, the two bars or sills E E' being curved upward at their ends and secured to the heel extensions of the finger-beam and back-beam at such distance apart as to make the width of the binder-frame substantially the same as that of the main frame, in rear of which it is located with the front of the one frame lapping the rear of the other, and the binder-frame so constituting an adjustable rear section or jointed extension of the main frame. A vertical front portion or gear-plate, E^2 , of the binder-frame supports all the gearing of the binding mechanism well forward on the binder-frame, close to the drive-wheel, to guard against exerting too much downward pressure upon the rear end of the main frame, and much the greater portion of the weight of the binder-frame and the parts mounted thereon is located outside of the line of tread of the drive-wheel, as will further on more fully appear.

The sills E E' are duplicates, and are made of metal—preferably steel—to secure strength and durability with lightness. Near the points at which they are curved upward in front the sills cross beneath and are firmly fastened to the finger-beam D^4 by means of bolts and angular brackets or clip-castings E^3 E^4 , which in this instance also in part serve for pivotally attaching the binder-frame and finger-beam to the main frame. These angular fastening-brackets, as best shown in Figs. 1, 3, 5, and 6, are exactly alike, except that one is "right" and the other "left." Each bracket is made to fit against the under side of the finger-beam, to which it is securely fastened, as by bolts e e ,

and is provided with a longitudinal flange projecting upward from its rear edge to bear against the back of the finger-beam and strengthen its connection therewith, and has also at one end, on its under side, a downwardly and forwardly projecting angular flange or rib, the portion e' of which flange fits against and is bolted to the inner side of the sill E or E' , while the front portion thereof constitutes an ear, e^2 , between which and the sill there is space sufficient to receive one of the rear branches or arms, b b , of the main frame. Pivot bolts or pins c^3 e^4 , passing through these main-frame arms and through the bracket-lugs e^2 e^3 and sills E E' , make the jointed connection between the main frame and binder-frame. The pivot-bolts are directly in line with each other for an obvious purpose.

Suitable fastening-brackets, E^5 E^6 , both of which are shown by dotted lines, Fig. 8, and their securing-bolts, serve to firmly connect the sills E E' near where they bend upward at their rear ends to the platform back-beam D^6 . These brackets are substantially alike except in size. One of them is clearly shown in Figs. 2 and 4, by inspection of which, in connection with Fig. 8, it will be seen that the brackets are of angular formation, being bolted by their rearwardly-extending lower portions to the sills, and bolted to the back-beam by their upwardly-extending portions.

Bars or metallic straps d^4 , d^5 , and d^6 are bolted or otherwise securely fastened to the finger-beam and to the platform back-beam by their bent rear ends. The platform bottom or boarding is fastened to these straps, which, or at least the intermediate one, d^5 , are by preference made of steel. The strap d^5 is made of runner shape, being curved upward at front to form a shoe or shoe-like projection, D^7 . The securing-bolt d^7 , which passes through the strap d^5 and finger-beam, also passes through a clip-fastening or angle-bracket, F , beneath the beam, and above the beam through the base of a stand or bracket-support for a reel-post, further on to be described.

The bracket F serves to pivotally connect the rear end of the draw-bar C^3 with the finger-beam at a point where it is braced by the runner-strap, and directly in line with the before-described two pivotal connections of the main frame with the binder-frame. As shown in Figs. 1, 5, 6, and 9, this bracket is provided with a perforated two-armed or slotted lug, to which the draw-bar is jointed by the pin or pivot-bolt f , and has a rear edge flange, f' , projecting upward to bear against the back of the finger-beam, and an offset or downwardly-projecting rear portion, F' , at and near one end, constituting a seat up against which the runner-strap d^5 bears. A bolt, f^2 , and the bolt d^7 serve to hold the finger-beam and bracket firmly together.

To facilitate construction and secure strength with lightness, the gear-supporting frame-plate E^2 is best made in the slotted or skeleton form shown and in a single casting, (malleable iron

or steel,) suitably flanged and ribbed. It has securing lugs or feet G G, by which it is rested upon and bolted to the sills E E', as shown in various figures of the drawings. The bolts g 5 g, by which the feet G G are secured to the sills, are relieved of the weight of the frame-plate and its mechanism by sustaining shoulders or flanges resting on the sills, as best shown by dotted lines in Fig. 6. The plate is 10 recessed or cut away between its feet, (see Figs. 5 and 6,) so as to straddle and pass well above the rear portions or arms, b b, of the main frame B, as well as above the crank-shaft C and its bearing b'. In this way the main-frame arms 15 may continue straight to their jointed connection with the binder-frame and finger-beam, instead of being curved or bent, as they would have to be to pass beneath the frame-plate were it made straight or unrecessed at its lower edge. The frame-plate straddles sufficiently 20 far above the main-frame arms and crank-shaft to allow of all requisite rocking movements of the binder-frame, finger-beam, &c., without causing the plate to come in contact 25 with the frame-arms or parts mounted thereon.

Besides the above-described connection of the gear-supporting plate E² and binder-frame sills, these parts are firmly connected together by stay-bolts or tie-rods G' G² and nuts. The 30 bolt G' is suitably attached at one end to the upturned portion of the sill E a short distance beneath its top or near its extreme end, and at its opposite threaded end passes through a hole provided for it in the gear-plate, and is 35 adjusted and secured by the jam-nuts g' g' on opposite sides of the plate. The bolt G² is secured at its opposite ends to the top of the upturned front end of the sill E' and to the gear-plate by the nuts g² g². By using two nuts for 40 securing each of the tie-rods to the gear-plate, as shown, these rods may be fixed against both pulling and thrusting strains, and the gear-plate and sills be thus firmly bound together. The front upturned end of the sill E is still 45 further braced and stiffened by means of a nearly upright standard or curved bar, G³, which also serves as an inner reel-support, and as a means of connecting the lifting-lever link a⁵ with the finger-beam, &c., as further on 50 explained. This trussing or stiffening bar is bolted at its lower end to the sill at g³, and is attached by a bolt at g⁴ to the end or top of the upturned portion of the sill. The inner 55 reel-support and sill are still further tied together by a firmly-attached bearing bracket or box, G⁴, for a shaft, G⁵, to be hereinafter more fully referred to. This box, as shown in Fig. 4, is secured to the reel-support and sill by bolts g⁵ and nuts. At their upturned rear 60 ends the sills E E' are firmly connected and braced together by a cross-bar or tie-piece, H, on top of them. Angle-pieces or corner-irons h h and bolts and nuts serve, as plainly shown in Fig. 8, to fasten the cross-piece and sill ends 65 together. The sills are also connected by a heavy sheet-iron band, H', and their rear ends thus further braced. As the length of the

binder-frame is greater than the width of the platform, a closely-floored rearwardly-projecting extension of the binder-frame is in this 70 way provided to support the head ends of long stalks of grain as delivered from the comparatively narrow platform. As will be understood from inspection of Figs. 1, 3, 4, and 8, the curved rear extensions of the binder-frame 75 sills have the sheet-iron secured to them by bolts or rivets passing through the sills and through flanged edged ribs or brackets h' h', which are riveted to the band.

A box-hanger or suspended bearing-support, 80 H², is connected to the cross-piece H by bolts. (See Figs. 2, 4, and 8.) A box-casting or bearing-bracket, H³, is bolted to the top outer corner of the cross-piece. A packer-shaft, H⁴, and a binder-arm shaft, H⁵, to be further on 85 more fully referred to, are supported in the bearings h² h³ of the box-hanger H² and box-casting H³.

A bracket or stand, F², serves to support a reel-post, F³, as well as a grain-eyener or butt-guide and its actuating mechanism, as in turn to be described. This supporting-bracket (see 90 Figs. 1, 5, 6, and 9) is shown as of angular or flanged form, and as provided with the rearwardly-projecting horizontal shank or attaching-arm F⁴, secured to the finger-beam D⁴ by the bolts d⁷ f² f³. The attaching-arm, as in this instance formed, is recessed at f⁴ to straddle the cutters, so that the cutter-bar and cutter-blades may be reciprocated freely and space 100 provided for escape of clogging substances beneath the stand. The upwardly-projecting lateral flange or inner wing, F⁵, of the reel-post bracket is curved to correspond with the curvature of the shoe or runner D⁷, to which it is 105 strongly secured by bolts f⁵, and has formed with or attached to it a bearing for the before-referred-to shaft G⁵. Upon the side of the stand opposite that from which the wing F⁵ projects another flange or wing, F⁶, is provided. 110 This outer wing, F⁶, is slightly curved horizontally and accommodates the reel-post-secur- 115 ing bracket to the butt-guide, further on de- scribed, the wing extending from the base portion or attaching-arm F⁴, in which it merges, 120 to the stand proper or upright main portion of the bracket, to which the reel-post is at- tached by bolts f⁶ and nuts, which also serve 125 to secure the inner divider, F⁷.

As, under the organization shown, all of the 120 automatically-working parts of the mechanism, except the cutters, have motion communicated to them through or by way of the shaft G⁵, this shaft will hereinafter be referred to as the "driving-shaft." It is, as before explained, sup- 125 ported at its opposite ends by the bearings of the bracket G⁴ and the rake-post stand. Mo- 130 tion is communicated to the driving-shaft from the main axle by means of a sprocket-wheel, I, on the axle, a chain, I', and a sprocket-wheel, i, fast on the driving-shaft near its inner end. A bevel-gear, I², by the side of this sprocket-wheel and fast on the shaft, and a second sprocket-wheel, i', fastened to the driving-

shaft at its outer end, are also provided. The bevel-gear I^2 serves to impart motion to the binder-gearing on the gear-plate E^2 , and the outer sprocket-wheel, i' , serves by means of a chain, I^3 , and other mechanism, such as next to be described, to actuate a reel and a butt-guide or grain-evener, K .

The chain I^3 passes over a sprocket-wheel, J , fastened on a reel-shaft, J' , which is provided with suitable bats or beater-arms, as usual, and is supported at one end in a bearing, h^4 , formed in a bracket, h^5 , bolted with the top of the inner reel-support, G^3 . The bearing-support j , for the other or outer end of the reel-shaft, is formed by one of two boxes provided by a bearing-bracket or box-casting, J^2 , made of flanged or angular form, so as to embrace two sides of the reel-post, to which it is strongly fastened by bolts passing at right angles with each other through the post, as shown in Figs. 6 and 9. The other box, j' , of the bearing-bracket J^2 supports a stud-shaft, j^2 , which is pinned in place, and has a sprocket-wheel, j^3 , and a bevel-gear, J^3 , loosely mounted on its outer end. This sprocket-wheel and bevel-gear are cast together or else rigidly connected, so as to turn with each other on their shaft. The sprocket-wheel is engaged and actuated by the reel-driving chain I^3 , and the bevel-gear J^3 engages a bevel-pinion, j^4 , fast on an upright rotating shaft, K' , to the lower end of which the butt-guide K is fastened. The upper end of this rotary shaft is mounted to turn freely in a swinging two-part box or divided bearing formed in a recessed or forked box-hanger or bearing-casting, J^4 , hung loosely on the shaft j^2 , so that it may swing thereon between the box j' and hub of the bevel-gear J^3 . The pinion j^4 , resting in the casting-recess or space between the upper and lower sections of the double bearing for the butt-guide shaft, and being securely fastened to this shaft, serves to support it and the butt-guide against vertical movement. The butt-guide and its shaft are adjustable toward or away from the platform, so as to adapt the butt-guide to act upon the grain to the greatest advantage as it is moved along the platform toward the place of binding, as further on explained. The butt-guide has a serrated or corrugated rim, or is in equivalent way provided with horizontally-extending projections on its periphery, to engage the butts of the grain and insure its proper evening action upon the stalks as it is rotated about its vertical or nearly vertical axis.

As shown by Figs. 10 and 11, the circular butt-guide is made hollow or of drum shape, with properly-roughened or tooth-like periphery, and of minimum weight, by the employment of light disks or wooden heads, k , to which the vertically-corrugated sheet-metal periphery k' is tacked or screwed. A light cast-metal tube, K^2 , fitting central perforations in the butt-guide disks, is provided with annular collars or flanges k^2 , to which the drum-heads or disks are bolted or otherwise se-

cured, and this tube serves to fasten the butt-guide to its shaft in suitable way. By thrusting and pulling upon the link D^2 by means of mechanism before described, the butt-guide is adjusted as its shaft is swayed by the reciprocations of a slide-bar, K^3 , to one end of which the link is connected, and in an oscillating box, K^4 , in the opposite end of which the butt-guide shaft is journaled near its lower end and above the butt-guide. The box K^4 is trunnioned or fitted to rock in the slide end in well-known way, the slide in this instance being perforated to receive the trunnion of the rocking bearing, while a nut fitted upon the reduced threaded end of the trunnion holds the parts together. The adjusting-bar K^3 is supported and guided in its movements by ways k^3 on a bracket, k^4 , bolted to the reel-post stand F^2 by two of the bolts f^6 , which connect the reel-post and inner divider with the stand. The dotted lines, Fig. 9, show the butt-guide as swung inward to act upon shorter grain than that which it would be suited to operate on when adjusted as shown in full lines. The driver, while in the seat A^4 , can readily adjust the butt-guide by operating the lever D' .

In order that the reel and the butt-guide, as well as the binder-gearing hereinafter to be described, may readily be thrown into and out of action, the driving sprocket-wheel I is connected with the axle A' by pawl-and-ratchet mechanism, essentially such in this instance as that fully set forth in my before-recited Patent No. 267,064, and as hereinbefore referred to in connection with the cutter-driving gearing. As shown in Figs. 14 and 15, the wheel I , which is mounted loosely on the axle between the inner frame-bracket, B' , and the draw-bar bracket a' , is provided with the internal ratchet-toothed annular rim or flange, I^4 , and these teeth are engaged by the spring-actuated pawl i^2 , pivoted to the pawl carrier or plate I^5 , which is fastened to the axle. The pawl has a laterally-projecting lug or spring-engaged side arm, i^3 , and the spring has an inclined shoulder or bend, i^4 , near its free end. It will be seen that when the pawl-arm is borne against by that part of the spring outside or beyond the shoulder the pawl-nose is held to the ratchet-teeth, while allowed to slip along them or "click" in backing, but locking the sprocket-wheel to the axle as the machine advances, and that when the pawl is swung inward at its nose to present its side arm to the spring inside of its shoulder, as shown by dotted lines in Fig. 15, the pawl-plate is disengaged from the sprocket-wheel, leaving this wheel loose on the axle and throwing the driving-shaft G^5 out of rotation, and stopping the action of all mechanism driven therefrom. The pawl-attached pin i^5 , passing through the slot i^6 in the pawl-plate, serves to set the pawl for connecting or disconnecting the sprocket-wheel and axle, and the abutment I^6 , close to or against which the heel end of the pawl works, relieves the pawl-pivot of injurious thrusting strains.

The platform is provided with a grain-deliverer or endless carrier, L, shown as formed of a series of belts, and as provided with adjusting mechanism in most respects identical 5 with or substantially similar to that set forth in the before-recited Patent No. 252,081. Instead of continuing the platform proper or bottom boarding, D⁵, to and beneath the carrier-rollers L' and L², as heretofore, this boarding 10 is confined within the area between the rollers, so that open spaces l' at the inner and outer ends of the platform, or inside of and beyond its boarding, are provided between the finger-beam and back-beam to permit of 15 the escape of clogging matter. The journal ends of the shaft l' of the driving-roller L' of the carrier are suitably mounted in the platform back-beam and in the binder-frame upright portion or gear-plate E². The finger-beam is 20 perforated for the passage of the roller-shaft to its bearing-support in the gear-plate. The adjustable or outer carrier-supporting roller, L², is mounted in sliding bearings or adjustable cross-heads l³ l³, (see Fig. 12,) which are 25 guided in ways secured to the finger-beam and back-beam, and are connected by the adjustable supporting-bar or cross-piece L³. This bearing-connecting piece is rendered stiff to 30 guard against any possibility of its springing or becoming bent by the transverse strains to which it is subjected. As shown, it is inclined at one edge both ways from its middle, or gradually widened from its ends toward its middle, so making it amply strong and rigid 35 at the point where greatest strength is needed, to stand unyieldingly the thrusting strains imparted by the adjusting-lever L⁴, which, as shown in Figs. 9, 12, and 13, is pivoted at one end to a bracket, l⁴, secured to the back of the 40 finger-beam, and connected midway its length with the cross-piece L³ by the links or straps L⁵ L⁵, or it might be by a single looped or bent strap embracing the cross-piece and passing around its straight edge. The straps are pivoted to the cross-piece and lever, and to 45 strengthen the connection of the parts a block, l⁵, is secured between the cross-piece and the lever, this block serving also to keep the straps separated sufficiently to afford a space for the 50 lever to vibrate in without being bound by the straps.

The ends of the canvas apron or belts of the carrier are connected by being bent or turned at a right angle, abutting these ends, fitting 55 them between clamping-pieces L⁶ L⁶, and securely uniting them by bolts l⁶, passing through said pieces and through slots in the belt ends and tightened by nuts. The carrier-adjusting lever L⁴ projects at its rear end through a slot 60 in the back-beam D⁶, and detent devices are provided to hold the lever in any position to which it may be adjusted, as in my former patent, No. 252,081. The carrier-belts are sustained against injurious sagging by means of 65 supports L⁸, arranged beneath the top portions of the belts, so that the adjacent edges of every two belts overlap and bear upon a

support. As shown in Figs. 3, 9, 12, and 13, each support is of cross shape or T form in transverse section, and may appropriately be 70 termed a "cross-head rib," and is composed of a top or head piece constituting the support proper, and a rib-piece secured at its top edge to the under side thereof, extending along the space between the adjacent edges of the bottom portions of two belts and fastened at its lower edge to the platform bottom or boarding D⁵. The belt-supports extend from near the lever L⁴ to or nearly to the inner end of the 75 platform.

A binding receptacle or support for the grain, as it is accumulated to form bundles for binding, is shown as mainly formed by the outwardly-projecting ends M' of a series (four in this instance) of spanner pieces or bridge-bars, 85 M, set edgewise on and secured to the binder-frame sills E E' crosswise thereof. Those portions of these sill-spanning-pieces which overhang the sill E' go to make up the binding-receptacle, which is in part formed by the correspondingly-projecting end of the platform back-beam D⁶, and by the knotting-mechanism casing or box N, which is supported by being suitably secured upon the cut-away ends of two of the bridging-pieces M, and by being 95 fastened by its forwardly-projecting arm or flanged extension N' and a bolt, n, to a lug, n', of the gear-plate E². The pieces M, bridging the space between the sills of the binder-frame, are cut away or concaved on their upper edges, and serve as an inclined or curved way along which the grain is moved to the binding-receptacle. These pieces are shown as attached to the sills E E' by being connected with strips m m, which are made fast to 100 other strips, m' m', bolted to the sills. Instead of the so-formed composite or two-part wooden angle-bars, by preference employed, angle-iron may be used—to secure to the binder-frame the bars for forming the skeleton or slotted bottomed way and receptacle. Three of these bars project at their inner ends into the spaces m², formed by annularly recessing the driving-roller L' between the belts of the carrier L. The curved or inclined ends of the bars 115 do not quite touch the roller. The inner end, m³, of the forward one of the bars M projects or laps slightly in front of the flanged forward end of the roller, being cut away or beveled on one side. The front ends of the pieces M 120 are below the level of the top surface of the carrier-roller, it should be noticed, so as not to obstruct the delivery of the grain.

A rock-shaft, M², suitably journaled at its ends in bearings in the platform back-beam, and in the frame-standard or gear-plate E², and passing through an opening in the finger-beam, has a series of cut-off rods, M³, fastened to it. The front one of these rods is shown as fixed to the rock-shaft just in front of the vertical 125 portion or back of the finger-beam, and it, as well as the rear one of the series of rods, is made straight, or may as well be so made, while each of the three intermediate rods of the 130

cut-off, which are arranged to vibrate in the spaces between the belts L, is curved at its end to correspond in shape with the top surface of the annular groove m^2 of the carrier-
5 roller, into which it descends beneath the level of the top surface of the carrier when rocked downward, with its end lapping and resting upon or slightly above the end of the piece M, which projects into the roller-groove.

10 Curved arms constituting a packer, N², secured to and rotating with the shaft H⁴, project between the bridge-bars M. This packer forces the grain, as delivered to it by the carrier L, along the way and packs it in the binding-receptacle, so that the pressure of the grain acting on appropriate starting or tripping mechanism may serve to throw the binding mechanism into action. Suitable devices for so starting the binding mechanism are shown in
15 the before-mentioned Patents Nos. 260,668, 261,591, and 261,590; and as such devices do not by themselves constitute any part of my present improvements, and may be variously modified, they need not in detail be described herein.

20 Both the packer N² and the binder gear P, hereinafter more fully referred to, are rotated in direction the opposite of that in which the corresponding parts are shown as adapted to be revolved in my inventions formerly patented
25 as above, and the grain passes to the binding-receptacle beneath the packer-shaft, instead of above it, as formerly. The packer-arms are secured in sets (four in a set in this instance) to their shaft, and are provided with clearers
30 or strippers M⁴—one for each of said sets. The clearers clean the grain from the packer-arms, and, as shown, (see Figs. 3, 4, 6, 7, and 8,) each clearer has a longitudinal central opening or slot for the packer-arms to rotate in, is supported at
35 its opposite ends by the packer-shaft and binder-arm shaft, and is formed of strap-iron turned or doubled edgewise upon itself and bent into peculiar shape, so that the series of clearers forms, with the bridge-bars M, a grain passage-
40 way, N³, leading to the binding-receptacle, and also partly constitutes this receptacle. Each of these slotted clearers is made adjustable, so as not only to vary the areas of the passage-way and the receptacle, but to admit of their
45 ready adjustment to correspond with each other in fitting the parts together. At their outer and upper ends, which are supported by being connected with the binder-arm shaft H⁵, the clearers are curved concentrically with the packer-shaft H⁴, so that when they are rocked vertically about the packer-shaft in adjusting them up or down their said ends will always occupy proper positions relatively to suitable securing devices mounted on the binder-arm
55 shaft to enable the clearers to be clamped in place.

The securing devices, as shown by Figs. 3, 4, and 8, comprise three brackets, N⁴ N⁵ N⁶, the brackets N⁵ N⁶ being fitted loosely and directly on the binder-arm rock-shaft H⁵, and the bracket N⁴ being cast with a non-turning sleeve-bearing or tubular frame-support, M⁵, which

incloses this rock-shaft from near its front end to the hub or attaching-sleeve of the binder-arm M⁶, fastened thereon. Each of these clearer-supporting brackets is curved on its surface against which the clearer bears, to correspond with the curvature of the outer end of the clearer, which slides upon the bracket in adjusting. The clearer-supporting bracket N⁵ is fitted loosely upon the binder-arm shaft, so as not to interfere with its free rocking, by means of a short sleeve or bearing-collar formed with the bracket and held against movement endwise the shaft by cross-pins n³ n³ passing through the shaft at the ends of bracket-sleeve. The bracket N⁶ is formed similarly to and mounted in the same way as the bracket N⁵, except that its bearing-sleeve n⁴ is extended at one end and made to abut against the bearing h³ of the binder-arm shaft, thus rendering necessary the employment of but one of the cross-pins n³, or its equivalent. Suitable holding devices—such as the cross-head bolts n⁵ and their nuts, Fig. 8—serve to clamp the clearers to their brackets, the bolt-shanks passing through the slots of the clearers and their heads being forcibly drawn down upon the clearer ends by the nuts.

In order that the lower or inner ends of the clearers may be supported so as to allow the clearers to rock about the packer-shaft H⁴ for adjustment and without interfering with the free rotation of the shaft, while also tending to prevent the rotation with the shaft of a sheath or inclosing-casing with which it is loosely fitted, to guard against the wrapping of grain about the shaft, this casing is made in sections—ten in all—as shown, and in the following manner: The first section, O, of the packer-shaft casing is composed of a tube fitted at its forward end upon a reduced projection or round tenon-like extension, o, of a bracket-bearing or detachable box, Q, (see Fig. 37 and dotted lines, Figs. 3 and 5,) bolted to the binder-frame stand or gear-plate E². The hub of the packer-gear Q', fast on its shaft, abuts against the forward end of the bearing Q, and the forward end of the casing-section O abuts against the tenon-base or shoulder of the bearing projection, as will readily be understood by inspection of Figs. 4 and 19 and the description hereinafter given of the sections O⁷ O⁸ o⁷ of the shaft-casing. The opposite end of the casing-section O extends nearly to the hub of the first set of packer-arms, N², and fits around a tenon-like projection on and abuts against the shoulder of a short sleeve-section, O', (see similarly-formed sleeves O⁷ o⁷, Fig. 19,) lugged or provided with an ear, o', to which one branch of the leading clearer M⁴ is suitably secured, as by bolt and nut or rivet. The hub of the first set of packer-arms is fitted upon and fastened to the packer-shaft between the casing-section O' and another loosely-fitted lugged section, O², to the lug o' of which the remaining branch of the leading-clearer is fastened. This section O² has an arm, o², upon it, for a purpose further on explained,

and the next section, O^3 , of the casing constitutes the hub of a loosely-mounted gear, o^3 , and the support of a rocking arm, O^4 , the functions of which will in turn be explained. The next section, o^4 , is provided with a seat-lug or flanged ear, o^5 , to which is bolted so as to rock about the packer-shaft one end of a vibrating compressor, O^5 , to be again referred to. The casing-section O^6 has an ear, o^6 , for attachment of one branch of the central clearer, M^4 , and the hub of the central set of packers is secured between this section O^6 and the next section O^7 . The section O^7 , in addition to having the ear o^7 for securing the clearer, has a reduced projection or round tenon-like end portion, o^8 , upon which fits one end of the section O^8 of the casing, the opposite end of this section similarly fitting on the tenon o^8 of the clearer-supporting section o^7 . The rear set of packer-arms is secured by its hub to the shaft between the clearer-bearing section o^7 of the casing and the final section, O^9 , of the casing, which serves to secure one branch of the last clearer and extends to the rear bearing, h^2 , of the packer-shaft.

The frame-tube and long bearing M^5 for the binder-arm rock-shaft is suitably secured, as by a flange or shoulder, m^4 , and bolts m^5 , (see Figs. 4, 5, and 6,) to the binder-frame stand or gear-plate E^2 , and the rock-shaft has the hub or attaching-sleeve m^6 of a crank, M^7 , detachably fastened to it and held firmly against any movement independently of it. At the opposite end this rock-shaft is secured in its bearing h^3 by a screw-bolt, n^6 , and its washer. The binder-arm rock-shaft, it will be noticed, serves as a brace or tie-rod for the binder-frame, as in connection with the gear-plate E^2 , the tie-rod G^2 , and the rear cross-piece, H , the ends of the sill E' are connected and firmly supported.

The tubular frame-support M^5 is shown as provided with brackets or lugs m^7 m^8 , to constitute bearings for supporting a rock-shaft to be actuated by a cord-clasper, and so, as set forth in the before-mentioned Patent No. 261,590, operate suitable clutch-tripping mechanism to start the binding mechanism. The bracket m^8 is also adapted to serve as a support for a tripper actuated by the binder-arm and operating on the cord-clasper to cause it to release the binding material and allow the gavels to be properly banded, as fully set forth in said patent.

The before-referred-to rocking arm O^4 is formed with or fixedly attached to the section O^3 of the packer-shaft casing, and serves as a "parting-arm" or auxiliary packer-arm to separate the grain to form a gavel, and which is inside the cut-off rods when they are uplifted from that on the grain-platform and direct it toward the binding-receptacle and bring it within the embrace of the binder-arm on its descent. This intermittently-actuated auxiliary packer-arm or parting-arm O^4 is operated by a rack-bar, R , having suitable pivotal or wrist-pin connection, or with the binder-arm near its

heel end or rock-shaft. This rack-bar engages the rack-gear of the parting-arm, and is prevented from becoming disengaged therefrom by a guide formed by a transverse way or slot in the arm o^2 on the clearer-supporting section O^2 of the packer-shaft casing. It will be seen that upon the downward rock of the binder-arm the parting-arm will be rocked from its normal position, in which it is represented in Fig. 6 and by dotted lines in Fig. 7, to the position in which it is shown by full lines in the latter figure. The point of attachment of the rack-bar to the binder-arm is such that the parting-arm will have very nearly completed its sweep by the time the point of the binder-arm has reached the position indicated by x , Fig. 7, by or slightly before which time the outer end of the parting-arm has reached a corresponding position, so that the grain swept along by it will be presented and held within the reach of the binder-arm. That but slight further movement is imparted to the parting-arm as the binder-arm completes its downward rock is due, as will readily be understood, to the fact that at such time the rack-bar is on and near the dead-center point in the motion communicated to it by the binder-arm. The parting-arm is returned to its normal position by being rocked backward in obvious way as the binder-arm ascends.

The vibrating compressor O^5 , supported so as to turn about the packer-shaft, as before explained, crosses the binding-receptacle so as to overhang the grain, as accumulating to form a gavel, and bear downward upon it in action with a movement comparatively rapid at first and gradually slowing down as the force of compression increases. This overhanging compressor is actuated by the binder-arm, with which, and near its shaft H^5 , the compressor has jointed connection. This connection between the compressor and binder-arm, as shown, (see Figs. 3, 6, 7, and 35,) consists of a pivoted and screw-threaded yoke or link, R' , jointed at r' to the compressor, and a threaded eyebolt, R^2 , having wrist-pin attachment at r^2 with the binder-arm and screwing into the threaded head of the yoke R' . By this means the connection may be lengthened or shortened to increase or diminish the amount of compression upon bundles of given size as well as to adapt the compressor for proper action upon bundles differing in sizes according to the adjustment of devices for throwing the binding mechanism into and out of action, such as explained in the before-mentioned patents granted for my invention, especially Patent No. 261,590. The compressor O^5 is curved upward at r^3 , to adapt it the better to act upon the grain by conforming in part to the shape of the bundle. (See Fig. 7.)

The bevel-gear I^2 of the driving-shaft G^5 meshes with a bevel-pinion, R^3 , formed with or made fast to a spur-gear, R^4 , which will hereinafter be termed the "driving-gear," as by way of it motion is imparted to the rest of the binder-gearing. This driving-gear and

its attached bevel-pinion are suitably mounted on a stud-support secured to the gear-plate E^2 . A pinion, R^5 , on the shaft l^2 of the driving-roller L^1 of the grain-carrier meshes with the driving-gear, and is continually rotated thereby. The pinion R^5 is loosely mounted on its shaft. A clutch and mechanism for shifting it engage and disengage this pinion and its shaft, so that the carrier is caused to operate intermittently. As shown in Figs. 3, 5, 20, 21, 22, 23, and 24, an annularly-grooved clutch-sleeve or sliding clutch-section, r^4 , connected with the shaft l^2 in well-known way for interlocking engagement with the pinion-attached or non-sliding section of the clutch, is positively moved along its shaft toward or from the pinion by shifting mechanism, thus causing engagement and disengagement of the pinion and its shaft without the use of a spring. The shifting mechanism consists of a vibrating lever or clutch-shipper, R^6 , forked or yoke-shaped at one end to engage the annular groove of the clutch-section r^4 , pivoted at its opposite end by a pin passing through lugs r^5 on the frame-plate E^2 , and through corresponding lugs, r^6 , of the shipper, and vibrated by means of a vertically-rocking cam-head or crank-block, R^7 , acting on a pin, r^7 , projecting downwardly from and fixed to the shipper. The cam of the crank block or head is formed by a groove, into which the controller-pin r^7 projects. This cam is fast on the cut-off rock-shaft M^2 , which is actuated by a connecting-rod, R^8 , pivotally attached at r^8 to the crank-block, and operated, as further on to be explained, when the binder-gear P is thrown into action. In this way, when the cut-off rods M^3 are elevated, and the cut-off thus caused to assume its operative position to arrest the grain, the carrier is stopped by the action of the cam-controlled shipper on the clutch, and when the rods of the cut-off are rocked down into their inoperative position the operation of the carrier begins again, as will readily be understood, the cut-off and carrier being intermittently in action and alternately operative, as in former patented inventions of mine hereinbefore referred to.

A doubly-toothed idle-pinion or fixedly-united pair of pinions, q q' , (shown detached in Fig. 25,) suitably mounted on the gear-plate E^2 , serve to communicate motion from the driving-gear R^4 to the packer-gear Q' , which in turn meshes with a pinion, Q^2 , for intermittently actuating the normally stationary binder-gear P , substantially as described and shown in the before-mentioned Patents Nos. 260,668 and 261,590. As in said patents, the pinion Q^2 has two face spurs or teeth, q q' , for engagement by a spring-actuated clutch-bolt or adjustable tooth, Q^3 , mounted to slide in a guide-way on the outer face of the binder-gear, this bolt being tripped by mechanism differing from that already patented to me only in respect to the positions of some of the parts and their arrangement relatively to each other, to

accommodate the before-referred-to change in the direction of rotation of the binder-gear.

The following changes made in the locations and relative arrangements of the clutch-tripping mechanism may be noted, referring to Figs. 3, 4, 6, 30, and 31, viz: The tripping-lever Q^4 crosses above instead of below the hub of the binder-gear, to act at its outer or catch end upon the rocking lever q^2 , which engages the clutch-bolt Q^3 , and this lever q^2 is pivoted above the clutch-bolt (considered as in its normal position) and the spring q^3 located below the bolt, whereas formerly the spring was arranged above and the lever below the bolt. The position of the fixed cam q^4 on the frame-plate E^2 to act on the lever q^2 is also appropriately changed, so that upon the completion of a revolution of the binder-gear the clutch-bolt will be left dogged by the catch of the tripping-lever Q^4 , with the toothless portion q^5 of the binder-gear opposite the pinion Q^2 . The connecting-rod R^8 for operating the cut-off is curved upward to clear the crank-shaft C or its bearing b' when the binder-frame is rocked downward at front, and is actuated by a mutilated pinion, S , having three side teeth or face-spurs, s s' s^2 , instead of two, as in the before-mentioned Patent No. 260,668, and operated by the binder-gear and its sliding tooth or clutch-bolt in such manner as to give to the cut-off rods their upward rock during the first part of the movement of the binder-gear, and rock them downward during the final portion of the revolution of said gear, thus having the binding mechanism and the carrier in action alternately, as in my prior patented inventions. Side teeth or face-spurs, S' and S^2 , on the binder-gear engage, respectively, with the spurs s and s^2 of the pinion S , to start it in motion, the balance of the movement to give the half-revolution required at each action of the pinion being imparted by the peripheral teeth and the clutch-bolt Q^3 , this clutch-bolt acting only on the side tooth, s' , of the pinion during its starting or half revolution, as will readily be understood by inspection of Fig. 5.

The binder-gear P , the pinions S , Q^2 , and q q' , and the driving-gear R^4 and its bevel-pinion R^5 are all mounted in the same way on the gear-plate E^2 , and description of the manner of mounting the binder-gear only will therefore be given. The hub of this gear fits about a shouldered tabular stud or thimble, S^3 , (see Fig. 36,) that portion of this stud on one side of its flanged shoulder s^3 , and which constitutes the journal for the gear-hub, being of larger diameter than the end S^4 on the opposite side of the shoulder. This reduced end is fitted in an opening in the gear-plate E^2 , being made of a length about corresponding with, or at least not exceeding, the thickness of the plate at the point of attachment of the thimble. A screw-bolt, S^5 , threaded at both ends, is provided with the end washers and nuts, s^4 s^4 , and with the intermediate nut, s^5 , to

5 bear against the internal shoulder, s^0 , of the thimble. In this way it will be seen that a secure attachment of the thimble to the gear plate or frame E^2 may be made without possibility of clamping the hub of the gear between the end nuts, s^4 s^4 , which bear on the thimble, and that the gear may be detached by removing that nut and washer which is at the end of the journal portion of the thimble, while leaving the bolt and thimble firmly connected with the frame.

10 Suitable controlling mechanism of the binder-arm consists, as shown, of the slotted crank M^7 of the binder-arm rock-shaft H^5 , adjustably connected by the pitman T with the binder-gear wrist-pin t , the binder-gear thus serving, as in my formerly patented improvements, (see Patent No. 260,668,) to oscillate the rock-shaft to throw the binder-arm into and out of 15 action. Instead of the binder-arm being locked during the knotting of the band ends by mechanism connected with and operating through or by way of the rock-shaft H^5 , as formerly, the binder-arm is locked while the pitman 20 works in the slot of the crank, as before, by being dogged at or near its point by a rocking arm, t' , engaging a shoulder, T' , of the binder-arm, as hereinafter to be described. Accidental rotation of the binder-gear is prevented 25 by means of a detent yieldingly engaging it in such manner that by positively-applied force the binder-gear may be started by overcoming the holding-power of the detent, which is ample to prevent the binder-gear from being accidentally started, as by the jolting of the machine. This detent, as shown, is formed by a 30 spring-arm, T^2 , fixedly secured to the frame-tube M^5 , and having a double or V -shape bend near its outer end to form a projection, t^2 , to 35 engage a correspondingly-shaped notch formed in an inclined lug or cam-rib, T^3 , on the outer face of the binder-gear. The bent or curved end of the detent rides along the incline to direct the detent-catch t^2 into the locking-notch on the completion of a rotation of the 40 binder-gear each time this gear is actuated, as will readily be understood.

45 The tying-bill or knotter-head t^3 and the rest of the knotting mechanism, including the 50 mechanism for actuating it by the binder-gear P , may be in all respects similar to corresponding parts of my improvements described and shown in the before-recited Patent No. 260,668, of July 4, 1882, and the cord clamping and 55 searing devices are the same as in said patent. Improved mechanism of the binder-gear for actuating the knotter-pinion T^4 , differing from that shown and described in said Patent No. 260,668, is in this instance shown; but as such 60 altered mechanism is not herein claimed, need not necessarily be employed in connection with the improvements which are hereinafter claimed, and, moreover, is fully described and claimed elsewhere by me, it is deemed unnecessary to herein describe it further than as 65 follows:

In Figs. 6 and 30 are shown cam-ledges or

guide-ribs T^5 t^4 t^5 t^6 and a sector-gear, T^6 , by which the various movements are given the knotter-pinion, which has the guide-teeth t^7 t^7 70 on its face next the binder-gear. In Fig. 35 the knotter-head t^3 is shown in full lines in its normal or resting position 1. From this position 1 the head is moved by being rocked upward to the position 2, in which it is represented by dotted lines, and next it is rocked downward again into position 3, as shown by dotted lines. The final rotary motion from position 3, in the direction indicated by the arrow 4, around to the resting position 1 is next given, 80 thus looping and knotting. The movement from position 1 to position 2 is the result of the peculiar construction of controlling mechanism which is not herein claimed, and therefore need not be in detail described. 85

The vertically-vibrating locking-arm or dog t' , for engaging the binder-arm nose near its point, is so mounted upon a rocking support that it may be moved by or with said support in one direction (to undog the binder-arm) and 90 be free to rock independently of its support in the opposite direction to yield to pressure of the binder-arm nose when the binder rocks downward, and after so yielding automatically engage with the locking-shoulder T' and hold 95 the binder-arm securely locked while a knot is being formed in the band about a bundle of grain. (See Figs. 7 and 35.)

The rocking support of the binder-arm dogging mechanism is shown as formed by a rock-shaft, U , (illustrated by Figs. 32 to 35, inclusive, and elsewhere in the drawings,) which is hereinafter termed the "tripping-shaft," as it serves to lock and release or trip the binder-arm dog, and also to lock and trip a device 100 for dogging the grain-retaining, gavel-compressing, and bundle-discharging mechanism, soon to be described. This shaft is suitably supported beneath and in the same vertical plane as the knotter-shaft X by bearings U' 105 U^2 , shown as formed on the under side of the knotter-box N and its flanged extension N' . The rocking dog t' is loosely mounted upon the outer or rearward end of the tripping-shaft U by means of an end-lugged hub or shoudered sleeve, u , formed with the dog. A spring, 110 U^3 , coiled about the dog-sleeve, is secured at one end to a cross-pin, u' , of the tripping-shaft, and bears at its opposite end against a pin, u^2 , secured to the dog. This spring 115 acts with a constant tendency to rock the dog upward, or else hold it rocked upward, to the limit of its movement in this direction, with the sleeve-shoulder bearing against the end of the cross-pin u' opposite that to which 120 the spring is attached. When, upon the descent of the binder-arm, the point of the binder-arm nose strikes the dog t' , this dog is rocked downward or against the force of its spring, which serves to rock it upward behind the shoulder T' of the binder-arm immediately upon the presentation of this shoulder to the dog. (See Figs. 4, 6, 32, and 33 for 125 the normal or inoperative position of the dog 130

t' , and Figs. 7 and 35 for its operative position.) The tripping-shaft U is held in its normal position by a spring, V , acting with a tendency to hold it at the limit of its movement in one direction, or else to rock it to such position, and a stop-arm or dog, V' , acting, in connection with other devices of suitable controlling mechanism, as further on to be described, to limit the movement of the tripping-shaft in the direction in which the spring serves to rock it. Suitable actuating mechanism of the tripping-shaft serves, as presently explained, to rock this shaft against the action of its spring. This spring V is coiled about the tripping-shaft, and bears at one end against an end lug or shoulder on the hub of the fixedly-attached dog and stop-arm V' . The opposite end of the spring is secured to the knotter-box or extension thereof. A fixedly-attached trip-arm or crank, U^4 , at the inner or front end of the tripping-shaft is acted upon, at the proper time to release the binder-arm from the dog t' , by a striker projection or tappet-like rib, w^3 , on the binder-gear. This tappet is more prominent than the notched rib T^3 , which is engaged by the spring brake-arm T^2 , and the tripping-arm U^4 is curved to clear said rib. The dog t' is rocked downward out of engagement with the binder-arm shoulder T' when the tripping-shaft arm is struck by the tappet, and immediately after its release the binder-arm rocks upward, leaving the dog t' free to assume its normal position upon the reverse rock of the tripping-shaft.

35 The stop-arm V' , in addition to its above-described function, serves to dog a rock-shaft, V^2 , against turning in one direction. A disk, v , fixedly secured on this shaft, has a cam-shoulder or ratchet-tooth-shaped projection, v' , formed upon its periphery, as plainly shown in Fig. 34, and these devices complete the controlling mechanism of the tripping-shaft. As will readily be understood by inspection of Figs. 4, 32, 33, and 34, the rocking movement of the tripping-shaft in one direction is limited by contact of the arm V' with this stop-disk, whether the arm engages the shoulder v' of the disk to dog the shaft V^2 or bears against some other portion of its periphery.

50 The shaft V^2 supports a grain-retainer or curved rocking arm, V^3 , against which the grain is accumulated in forming a gavel for binding. This retainer is fastened on the outer or rearward end of its shaft in such position as to form a part of the binding-receptacle, the grain being arrested by it by being pressed against it about midway the length of the stalks, or near where they are encircled by the binding material. The retainer proper, or that part of the arm V^3 against which the grain is accumulated, and which, when in its normal position, projects upward from the shaft V^2 , is curved to approximately conform to the shape of a bundle of grain. This arm is secured about midway its length, preferably a little nearer its lower than its upper end, to its shaft, and is made of angular form, (about L shape,)

being provided with the curved and slotted arm V^4 at its lower end. By thus extending the arm V^3 below its shaft and providing it with the side arm, V^4 , and an auxiliary pivoted arm, V^5 , it is made to discharge the bound bundles with certainty, as further on to be explained. The pivoted arm V^5 is formed to correspond in shape with the arm upright portion or part V^3 of the angular arm $V^3 V^4$, and is hinged at its upper end to the corresponding end of the retainer-arm by the pivot v^2 . At its lower end the pivoted arm is connected by a guide-pin, v^3 , with the slot v^4 of the arm V^4 . A lateral projection or lug, v^5 , is provided on the pivoted arm, for a purpose soon to be explained.

The shaft V^2 is supported in suitable bearings, $W w$, shown as formed with the knotter-box N and its flanged attaching-arm or extension N' , and in addition to the disk v , fastened to it at one side of its bearing w , has an actuating-lever, w' , and segment-gear w^2 secured to it at its end, or on the opposite side of said bearing. This lever and gear are shown (see Fig. 34) as formed in a single piece, the lever end of the piece being longer than the gear end. Projections $W' W^2$ on the inner face of the binder-gear P , at its periphery, and a sector-gear, W^3 , also on the inner face of said gear, serve to actuate the lever w' and gear w^2 , to impart the desired movements, as presently to be explained, to the grain-retaining, gavel-compressing, and bundle-discharging mechanism.

When grain is being packed into the receptacle against the rocking retainer, this retainer is held in its normal or dogged position (see the full lines, Figs. 6 and 35, and dotted lines, Fig. 7) by the engagement of the dog V' with the shoulder of the disk v , as shown in various figures of the drawings. (See particularly Fig. 34.) After the gavel has been accumulated and the binding mechanism thrown into action—thus rocking down the binder-arm, actuating the vibrating overhanging compressor O^5 , banding the bundle, and dogging the binder-arm—the retainer or rocking arm V^3 is caused to perform its compressing function by the contact of the binder-gear projection W' with the lever w' . In this way the lever w' is moved from its normal position 1 (shown by full lines, Fig. 34) to position 2, (shown by dotted lines in said figure,) and the retaining and compressing arm V^3 is forcibly rocked from the position in which it is shown in dotted lines, Fig. 7, and full lines, Fig. 35, inward against the grain, compressing the bundle to an extent sufficient to provide enough slack in the band (that portion, y , of the binding material which has been caused to encircle the bundle) to supply cord to form the knot from the band, instead of drawing it from the source of supply. By inspection of Fig. 7 it will be seen that the compression of the bundle in the receptacle previous to the action of the rocking compressor V^3 is due to the pressure of the binder-arm and the overhanging vibrating

compressor, aided by the tension of the binding material, thus leaving the bundle somewhat misshapen, as indicated by the bulging portion of the band shown in dotted lines, and 5 providing for the subsequent supply of cord from the band to form the knot as the bundle is finally compressed into smaller compass. From position 2 (see Fig. 34) the gear-lever w' and gear w^2 are next rocked into position 3 10 (shown by dotted lines) by the action of the sector-gear W^3 of the binder-gear on the gear w^2 , the direction in which the rock-shaft V^2 turns at this time being the reverse of that in which it rocks to bring the parts into position 15 2. The movement imparted to the rock-shaft to bring the gear and lever into position 3 causes the discharge of a bound bundle, the 20 rocking retainer, compressor, and discharger assuming the position in which it is shown by dotted lines in Fig. 6. Previous to the time of discharging the bundle the tripping-shaft U is actuated to rock the dogs t' V' , for releasing the binder-arm and the shaft V^2 and allowing the binder-arm to ascend. After dis- 25 charging the bundle the rock-shaft V^2 is actuated by the contact with its lever of the projection W^2 of the binder-gear, thus moving this lever into position 2, and bringing the retainer-arm V^3 into the position in which it is 30 represented by dotted lines in Fig. 35 and full lines in Fig. 7. The pressure of grain against the retainer rocks it into its normal or dogged position and brings the lever w' into position 1. A suitable stop, such as the rod Z crossing 35 between two of the pieces forming the receptacle-bottom, serves to limit the movement of the retainer-arm and prevent its being thrown too far inward by the action of the projection W^2 on the rock-shaft lever.

40 To insure the discharge of the bundles, the jointed member V^5 of the discharger is caused to rock on the pivot with which it is connected at one end with the main member, and to assume the position in which it is shown in dotted lines, Fig. 6, by a stop, Z' , against which its side projection, v^5 , strikes. This stop arrests the jointed arm before the completion of the rock of the retainer, and, as shown in Figs. 3 and 4, (see also Fig. 6,) is formed by a rod 45 bent, flattened, and perforated, and secured by a bolt and nut. When the discharger is rocked back into its normal position, the pivoted arm, if not falling by gravity into its corresponding position, will be caused to shut against 50 the side of the main arm of the retainer by the pressure of the grain as supplied to the binding-receptacle. By the employment of this pivoted arm it will be seen that it is rendered impossible for the bundle to become entangled 55 with the arm V^4 of the discharger, so as to be carried back into the receptacle or dogged along with the machine, and the advantage of employing the arm V^4 is obvious, as it enables the discharger to readily move the bundle 60 away from beneath the vibrating compressor O^5 , instead of acting to force the bundle up against this compressor, as would be the re-

sult were the discharger made without the arm V^4 while mounted and given the movements as hereinbefore described.

I claim as of my own invention—

1. The combination, substantially as hereinbefore set forth, of the driving-wheel, the axle, the rocking main frame surrounding the driving-wheel and closer thereto at the inner 75 than at the outer side, the tongue jointed to the inner front corner of the main frame, the cross-bar secured to the tongue in advance of the main frame and extending outside or beyond it, and the driver's seat supported by 80 said cross-bar well outside of the main frame and in advance of the axle, for the purpose described.

2. The combination, substantially as hereinbefore set forth, of the driving-wheel, the 85 axle, the rocking main frame surrounding the driving-wheel, the tongue hinged to the inner front corner of the frame, the brace connecting the tongue and outer front corner of the frame, the cross-bar supported by the tongue 90 and brace in advance of the frame, and the driver's seat mounted on said cross-bar outside of the frame, for the purpose described.

3. The combination, substantially as hereinbefore set forth, of the driving-wheel, the 95 axle, the rocking main frame suspended from the axle, the finger-beam crossing from side to side of the main frame, and having pivotal connections with the rear arms thereof, the hinged tongue, the draw-bar jointed to the inner front corner of the main frame, and having 100 pivotal connection at its rear end with the finger-beam in line with the connections between the finger-beam and the arms of the main frame, and the hanging bracket by which 105 the draw-bar is connected with the axle, for the purpose described.

4. The combination of the driving-wheel, the axle, the main frame surrounding the driving-wheel and having the rear arms, the brackets 110 by which the main frame is suspended from the axle closer to the driving-wheel at the inner than at the outer side thereof, the finger-beam having pivotal connection with the rear arms of the main frame, the tongue hinged to 115 the inner front corner of the main frame, the draw-bar correspondingly hinged to the frame, the hanging bracket by which the draw-bar is suspended from the axle, and the pivotal connection between the draw-bar and the finger-beam, substantially as and for the purpose 120 hereinbefore set forth.

5. The combination of the main frame, the hinged tongue, the tongue-attached cross-piece in advance of the main frame, the rock-shaft 125 mounted in bearings connected with the tongue and cross-piece, mechanism connecting the rock-shaft and main frame, and the rocking lever and detent devices of the rock-shaft, by which to rock the main frame about the axle 130 and secure it as adjusted, substantially as and for the purpose hereinbefore set forth.

6. The combination, substantially as hereinbefore set forth, of the driving-wheel, the axle,

the rocking main frame, provided at front with the sector-gear, the hinged tongue, the tongue-attached cross-piece, the brace connecting the tongue and main frame, the rock-shaft provided with the pinion engaging the sector-gear of the frame, and the lever and detent devices of said rock-shaft, for the purpose described.

7. The combination of the rocking main frame, the hinged tongue, the rock-shaft supported in advance of the main frame and acting thereon by connecting mechanism, the lifting and lowering lever mounted loosely on the rock-shaft, the pawl pivoted to said lever and controlled by a link and handle, the detent-wheel fast on the rock-shaft and engaged by the lever, the rocking holding-dog, and the crank thereof, substantially as and for the purpose hereinbefore set forth.

8. The combination of the main frame, the hinged tongue, the tilting-lever, its connecting-link, the rock-shaft in advance of the main frame, and upon which the tilting-lever is mounted loosely, and the detent devices of said lever, substantially as and for the purpose hereinbefore set forth.

9. The combination of the main frame, the hinged tongue, the cross-bar attached thereto in advance of the main frame, the rock-shaft parallel with said cross-piece, the lifting and lowering lever mounted on the rock-shaft, and the tilting-lever, also mounted on said rock-shaft, substantially as and for the purpose hereinbefore set forth.

10. The combination of the driving-wheel, the rocking main frame closely inclosing it on the inner side, and projecting therefrom on the outer side, the binder-frame rigidly connected with the finger-beam and grain-platform, and extending for the greater portion of its width outside the center of the line of tread of the driving-wheel, and means by which the finger-beam is pivotally connected to the rearwardly-projecting arms of the main frame, substantially as and for the purpose hereinbefore set forth.

11. The combination of the driving-wheel, the rocking main frame extending for the greater portion of its width outside the center of the line of tread of the driving-wheel, and the binder-frame sills lapping the rear of the main frame, having hinged connection therewith, and determining the width of the binder-frame, substantially as and for the purpose hereinbefore set forth.

12. The combination of the curved sills, the finger-beam, and the platform back-beam, substantially as and for the purpose hereinbefore set forth.

13. The combination, substantially as hereinbefore set forth, of the driving-wheel, the axle, the main frame projecting from the driving-wheel at the outer side, means for rocking the main frame about the axle, the rear arms of the main frame, the binder-frame having hinged connection with the main-frame arms, and extending for the greater portion of its

width outside the center of the line of tread of the driving-wheel, and the gear-plate of the binder-frame, supporting the gearing of the binding mechanism well forward on the binder-frame, for the purpose described.

14. The combination of the main frame, the binder-frame sills lapping the rear of the main frame and hinged thereto, the finger-beam, and the platform, substantially as and for the purpose hereinbefore set forth.

15. The combination, substantially as hereinbefore set forth, of the main frame, its rear arms, the curved sills of the binder-frame in rear of the main frame, the finger-beam, the platform, the platform back-beam, and the pivotal connections between the main-frame arms and the binder-frame, for the purpose described.

16. The combination, substantially as hereinbefore set forth, of the main frame, the finger-beam, the binder-frame sills crossing beneath and extending in advance of the finger-beam heel, and the clip-castings bolted to the finger-beam heel and sills, and pivotally connected with the arms of the main frame.

17. The combination of the finger-beam heel, the binder-frame sills, and the angular clip-castings fitting against the under side of the finger-beam heel and inner sides of the sills, and provided with the ears for pivotal connection with the main frame, substantially as hereinbefore set forth.

18. The combination of the main-frame rear arms, the binder-frame sills, the clip-castings having the ears between which and the sills the binder-frame arms are received, and the pivot-bolts passing through the ears, the frame-arms, and the sills, substantially as and for the purpose hereinbefore set forth.

19. The angular bracket or clip-casting constructed as described, to be fitted to the finger-beam heel and for attachment to the binder-frame sill, and having the pivot-receiving lug, as and for the purpose set forth.

20. The combination, substantially as hereinbefore set forth, of the driving-wheel, the axle, a rocking main frame extending for the greater portion of its width outside the center of the line of tread of the driving-wheel, a hinged tongue, a driver's seat outside the main frame and in advance of the axle, a binder-frame in rear of the driving-wheel, pivotally connected with the main frame, and extending for the greater portion of its width outside the center of the line of tread of the driving-wheel, a finger-beam and grain-platform having rigid connection with said binder-frame, and mechanism for raising and lowering the binder-frame and the finger-beam and platform.

21. The combination, substantially as hereinbefore set forth, of the driving-wheel, the axle, a rocking main frame extending for the greater portion of its width outside the center of the line of tread of the driving-wheel, a hinged tongue, a driver's seat outside the main frame and in advance of the axle, a binder-frame in rear of the driving-wheel,

5 pivotally connected with the main frame and extending for the greater portion of its width outside the center of the line of tread of the driving-wheel, a finger-beam and grain-platform having rigid connection with said binder-frame, mechanism for raising and lowering and means for tilting the binder-frame and the finger-beam and platform.

10 22. The combination of the platform, the finger-beam, the curved or runner-shaped strap secured to the bottom of the platform, and to the finger-beam, and the angle-bracket interposed between the finger-beam and strap, substantially as and for the purpose hereinbefore set forth.

15 23. The combination of the draw-bar, the lugged angle-bracket to which it is pivoted, the finger-beam, the strap, and the securing-bolt passing through the bracket, strap, and finger-beam, substantially as and for the purpose hereinbefore set forth.

20 24. The combination of the binder-frame sills and the gear-plate provided with the securing-feet and sustaining-shoulders and recessed between the feet, substantially as and for the purpose hereinbefore set forth.

25 25. The combination, substantially as hereinbefore set forth, of the main frame having the rear arms, the binder-frame sills pivotally connected with said arms, and the binder-frame gear-plate secured to the sills and recessed between them to straddle and pass well above the main-frame arms.

30 26. The combination of the rocking main frame, its rear arms, the cutter-actuating crank-shaft, the finger-beam, the binder-frame hinged with the finger-beam to the arms of the main frame, and the gear-plate of the binder-frame recessed to straddle and clear 40 the main-frame arms and the crank-shaft, substantially as hereinbefore set forth.

35 27. The combination of the binder-frame curved sills, the gear-plate bolted thereto, and the stay-bolts connecting the gear-plate and 45 the upturned front ends of the sills, substantially as hereinbefore set forth.

40 28. The combination of the binder-frame curved sills, the gear-plate, the stay-bolts attached to the sills, and the jam-nuts of these 50 bolts on opposite sides of the gear-plate, substantially as and for the purpose hereinbefore set forth.

45 29. The binder-frame curved sill E, trussed or stiffened at its upturned front end, substantially as and for the purpose hereinbefore set forth.

55 30. The combination of the binder-frame curved sill E and the inner reel-support attached at its lower end to the sill, and bolted 60 to the upturned end thereof, substantially as hereinbefore set forth.

65 31. The combination of the main frame, the binder-frame pivotally connected to the rear of the main frame, and the inner reel-support rigidly attached to the binder-frame, substantially as and for the purpose hereinbefore set forth.

32. The combination of the binder-frame curved sill E, the inner reel-support, the bolts connecting it with the sill, and the bearing-bracket, also connecting the sill and reel-support, substantially as and for the purpose hereinbefore set forth.

70 33. The combination, substantially as hereinbefore set forth, of the main frame, the rigidly-united binder-frame and finger-beam hinged thereto, the tilting-lever, the inner reel-support, and the link connecting the tilting-lever with said support.

75 34. The combination of the binder-frame sills, upturned at their rear ends, and their connecting and bracing cross-bar, substantially as and for the purpose hereinbefore set forth.

80 35. The combination of the binder-frame curved sills, the platform back-beam to which the sills are attached, and the cross-bar connecting the upturned rear ends of the sills above said back-beam, substantially as and for the purpose hereinbefore set forth.

85 36. The combination, substantially as hereinbefore set forth, of the binder-frame sills and the band connecting their upturned rear ends.

90 37. The combination, substantially as hereinbefore set forth, of the binder-frame sills having the upturned rear ends, the top cross-bar, and the sheet-iron connecting-band.

95 38. The combination of the binder-frame, having the upwardly-curved and rearwardly-projecting extension, and the grain-platform of a width less than the length of the binder-frame, substantially as and for the purpose hereinbefore set forth.

100 39. The combination of the binder-frame curved sills, the cross-piece connecting their upturned rear ends, and the box-hanger for the packer-shaft, substantially as hereinbefore set forth.

105 40. The combination of the binder-frame curved sills, the cross-piece connecting their upturned rear ends, and the bearing-bracket for the binder-arm shaft, substantially as hereinbefore set forth.

110 41. The combination of the finger-beam, the reel-post bracket attached thereto, and the runner, also attached to the finger-beam, and to which the bracket is bolted by its curved wing, substantially as and for the purpose hereinbefore set forth.

115 42. The combination of the finger-beam, the runner bolted thereto, the reel-post bracket, provided with a bearing and bolted to said runner and to the finger-beam, and the driving-shaft turning in said bearing, substantially as and for the purpose hereinbefore set forth.

120 43. The reel-post bracket formed, substantially as described, with the attaching-arm, and the inner and outer wings, for the purpose specified.

125 44. The combination of the main frame rocking about the axle, the binder-frame hinged thereto, the driving-shaft actuated from the axle, the bearing-bracket of the binder-frame, in which one end of the driving-shaft is mounted, the finger-beam rigidly connected with the

- binder-frame, and the reel-post stand secured to the finger-beam and provided with a bearing for the other end of the driving-shaft, substantially as and for the purpose hereinbefore set forth.
45. The combination, substantially as hereinbefore set forth, of the axle, the sprocket-wheel thereon, the driving-shaft, its sprocket-wheel, the chain passing round said sprocket-wheels, the bevel-gear on the driving-shaft near its inner end, the binder-gearing actuated by said bevel-gear, the sprocket-wheel at the outer end of the driving-shaft, and the reel-driving chain.
46. The combination of the finger-beam, the reel-post bracket, the reel-post bolted thereto, the binder-frame, the inner reel-support, the reel-shaft, the sprocket-wheel thereon, its driving-chain, the driving-shaft, and the sprocket-wheel at its outer end, substantially as and for the purpose hereinbefore set forth.
47. The combination, substantially as hereinbefore set forth, of the axle, the driving-shaft actuated therefrom, the reel-shaft, the rotary butt-guide, the reel-driving chain actuated by the driving-shaft, and the butt-guide-actuating sprocket-wheel driven by the reel-driving chain.
48. The combination, substantially as hereinbefore set forth, of the reel-post, the reel-shaft, the sprocket-wheel on the reel-shaft, the reel-driving chain, the stud-shaft attached to the reel-post, the rotating shaft of the butt-guide supported by said stud-shaft, and gearing driven by the reel-driving chain for actuating the butt-guide shaft.
49. The combination of the butt-guide shaft, the swinging box-hanger in which its upper end is mounted to turn freely, the stud-shaft by which said box-hanger is supported, and the gearing by which the butt-guide shaft is actuated, substantially as and for the purpose hereinbefore set forth.
50. The combination of the reel-post, the reel-shaft, the reel-driving chain, the butt-guide, its rotating swinging shaft, gearing driven by the reel-driving chain for actuating the butt-guide shaft, and mechanism for adjusting the butt-guide by swaying its shaft, substantially as and for the purpose hereinbefore set forth.
51. The combination, substantially as hereinbefore set forth, of the rotating butt-guide, its swinging shaft, the reel-post mechanism for supporting the butt-guide shaft at its upper end by the reel-post, and adjusting mechanism connected with the butt-guide shaft near its lower end, for the purpose described.
52. The combination of the rotary butt-guide, its swinging shaft, the adjusting-bar with which the butt-guide shaft is connected, the link attached to the adjusting-bar, and the rock-shaft provided with the lever and detent devices, and with which the link is connected, substantially as and for the purpose hereinbefore set forth.
53. The combination of the reel-post, the swinging rotating butt-guide shaft, its sus-
- pending connection with the reel-post, the adjusting-bar, its guideways, and the oscillating box of said bar, in which the butt-guide shaft is journaled, substantially as and for the purpose hereinbefore set forth.
54. The combination of the reel-post, the box-casting secured thereto, the stud-shaft fixedly attached to the reel-post by said casting, the sprocket-wheel and bevel-gear loosely mounted on the stud-shaft, the butt-guide shaft, the swinging two-part box in which it is mounted to swing about the stud-shaft, and the bevel-gear fastened to the butt-guide shaft, substantially as and for the purpose hereinbefore set forth.
55. The combination of the reel-post, the butt-guide, the swinging rotating butt-guide shaft, its suspending connection with the reel-post, the adjusting-bar, the oscillating box thereof, in which the butt-guide shaft is journaled, the supporting-bracket of the reel-post, and the guideway-bracket of the adjusting-bar secured thereto, substantially as and for the purpose hereinbefore set forth.
56. The combination of the grain-carrier, the circular butt-guide, and its rotating vertical shaft adjustable by swinging, substantially as and for the purpose hereinbefore set forth.
57. The combination of the finger-beam, the platform back-beam, the endless carrier, its adjustable roller, the sliding bearings, the stiff cross-piece inclined both ways from its middle and connecting the sliding bearings, the adjusting-lever, the bracket secured to the finger-beam, and to which the lever is pivoted, and the connection between the lever and the cross-piece, substantially as and for the purpose hereinbefore set forth.
58. The combination, substantially as hereinbefore set forth, of the platform, the series of carrier-belts, and the cross-head ribs between the belts for sustaining the carrier against sagging.
59. The combination of the binder-frame sills, the bridge-bars secured edgewise on and crosswise of the sills, and overhanging the outer one thereof, and the knotter-box thereon, substantially as and for the purpose hereinbefore set forth.
60. The combination, substantially as hereinbefore set forth, of the binder-frame sills, the bridge-bars secured thereto, and constituting the slotted bottom of a way along which the grain is moved to the binding-receptacle, the carrier, and the driving-roller thereof, provided between the carrier-belts with the annular grooves into which the inclined ends of the bridge-bars project, for the purpose described.
61. The combination of the cut-off rods, their rock-shaft, the carrier-belts, and the driving-roller thereof, having the annular grooves into which the curved ends of the cut-off rods descend, substantially as hereinbefore set forth.
62. The combination of the rotating packer-shaft, the series of adjustable clearers, and the packer-arms acting upon the grain in the pas-

sage-way and delivering it to the grain-receptacle, substantially as and for the purpose hereinbefore set forth.

63. The combination of the packer-arms, the series of adjustable clearers, and their supporting-shaft, about which they rock while being adjusted, substantially as and for the purpose hereinbefore set forth.

64. The combination of the rotating packer, the bridge-bars between which the packer-arms project, and the series of adjustable clearers by which the grain is stripped from the packer-arms above the bridge-bars, substantially as and for the purpose hereinbefore set forth.

65. The combination, substantially as hereinbefore set forth, of the packer, the packer-shaft, the binder-arm shaft, and the packer-clearers supported by said shafts.

66. The combination, substantially as hereinbefore set forth, of the packer-shaft, the packer-clearers adjustable by rocking about said shaft, the binder-arm shaft, and the securing devices by which the clearers are clamped in place.

67. The combination of the binder-arm rock-shaft, the clearer-supporting bracket, (or brackets,) fitted loosely on the rock-shaft and held against movement endwise thereof, the adjustable clearer, (or clearers,) mounted to rock during adjustment, and the clamping devices, substantially as and for the purpose hereinbefore set forth.

68. The combination of the binder-arm rock-shaft, the frame-tube in which it is mounted, the clearer-supporting bracket of said frame-tube, the clearer mounted to rock about its support, and the clamping devices, substantially as and for the purpose hereinbefore set forth.

69. The combination, substantially as hereinbefore set forth, of the packer-shaft, its casting, and the clearers rocking about said shaft during adjustment, for the purpose described.

70. The combination of the rotating packer-shaft, the sets of packer-arms secured by their hubs to this shaft, the lugged sleeves on opposite sides of the packer-arm hubs, and the clearers secured thereto, substantially as and for the purpose hereinbefore set forth.

71. The combination of the binder-frame, the rotating packer-shaft, the packer-gear, the bracket-bearing supporting the forward end of the packer-shaft and having the tenon-like projection, the first section of the packer-shaft fitted upon said projection, the rear bearing of the packer-shaft, and the packer-arms, the clearer-attaching sleeves, and the sections of the packer-shaft casing between the rear bearing and first section of the packer-shaft.

72. The combination of the rotating packer-shaft, the clearer-supporting casing-section O^7 , having the round tenon-like end, the casing-section O^8 , and the clearer-supporting section O^7 , also having the tenon-like end, substantially as and for the purpose hereinbefore set forth.

73. The combination of the binder-frame curved sills, the cross-piece connecting their upturned rear ends, the gear-plate connected with the sills, the tube secured to the gear-plate, the binder-arm rock-shaft mounted in said tube, the rear bearing for the rock-shaft secured to the sill-connecting cross-piece, the crank secured to the front end of the rock-shaft, and the securing devices at its opposite end, substantially as and for the purpose hereinbefore set forth.

74. The combination of the grain passage-way, the rotating packer, and the intermittently-actuated parting-arm rocking about the packer-shaft, substantially as and for the purpose hereinbefore set forth.

75. The combination of the packer-shaft, the parting-arm rocking thereon, the rocking binder-arm, and the mechanism for actuating the parting-arm connected with the binder-arm near its heel end, substantially as and for the purpose hereinbefore set forth.

76. The combination of the packer-shaft, the parting-arm rocking thereon, the rocking binder-arm, the rack-bar connected thereto and engaging the gear of the parting-arm, and the guide for preventing disengagement of the rack and gear, substantially as hereinbefore set forth.

77. The vibrating compressor mounted on the packer-shaft and crossing the binding-receptacle, substantially as and for the purpose hereinbefore set forth.

78. The combination, substantially as hereinbefore set forth, of the packer-shaft, the vibrating compressor mounted thereon, and the rocking binder-arm actuating the compressor.

79. The combination of the gear-supporting tubular stud, shouldered internally and externally and flanged near one end, and the bolt, threaded at both ends and provided with the nuts at the internal shoulder and ends of the tubular stud in which it is fitted, substantially as and for the purpose hereinbefore set forth.

80. The combination, substantially as hereinbefore set forth, of the gear-plate, the binder-gear, (or other member of the gearing,) the tubular stud, shouldered internally and externally and flanged near one end, the bolt threaded at both ends, and the securing nuts and washers by which the stud and bolt are clamped together at the internal shoulder and ends of the stud, and the stud and gear secured in place.

81. The combination of the binder-arm, its rock-shaft, the controlling mechanism of the binder-arm, the vibrating dogging-arm, first actuated by and yielding to the pressure of the binder-arm nose, and then engaging therewith, when the binder-arm is rocked downward, and mechanism for tripping the dog to release the binder-arm preparatory to its upward rock, substantially as and for the purpose hereinbefore set forth.

82. The combination, substantially as hereinbefore set forth, of the binder-arm, its rock-shaft, the controlling mechanism of the binder-

arin, the vibrating dogging-arm yielding to the pressure of the binder-arm nose and engaging therewith, when the binder-arm is rocked downward, and the spring by which 5 the dogging-arm is caused to engage the binder-arm nose and hold it during the knotting of the band ends.

83. The combination, substantially as hereinbefore set forth, of the rocking binder-arm, 10 the vertically-vibrating yielding dog engaging the binder-arm nose when rocked downward and during the knotting of the band ends, mechanism for actuating the dog to release the binder-arm preparatory to its upward rock, the 15 binder-gear by which said mechanism is actuated, and controlling mechanism of the binder-arm, also actuated by said gear.

84. The combination of the rocking binder-arm having the shouldered nose, the spring- 20 actuated vibrating dog for engaging therewith, and the tripping-shaft upon which the dog is mounted, and by the oscillation of which the dog is rocked to release the binder-arm, substantially as and for the purpose hereinbefore 25 set forth.

85. The combination of the tripping-shaft, the spring acting thereon, the spring-actuated dog for engaging the binder-arm, the controlling mechanism of the tripping-shaft, and the 30 actuating mechanism thereof, substantially as and for the purpose hereinbefore set forth.

86. The combination, substantially as hereinbefore set forth, of the binder-arm, its rock-shaft, the binder-gear, the controlling mechanism 35 of the binder-arm, the tripping-shaft, its actuating mechanism, and the dog for engaging the binder-arm nose, mounted on the tripping-shaft.

87. The combination of the binder-arm having the shouldered nose, the tripping-shaft, the 40 vibrating dog for engaging the nose of the binder-arm, provided with the end-lugged hub and loosely mounted on the tripping-shaft, the cross-pin of the tripping-shaft, and the spring 45 acting on the dog, substantially as and for the purpose hereinbefore set forth.

88. The combination, substantially as hereinbefore set forth, of the tripping-shaft, its spring, the vibrating dog for engaging the 50 binder-arm nose, yieldingly mounted on the tripping-shaft, the trip-arm of said shaft, and the tappet of the binder-gear acting on said trip-arm.

89. The combination, substantially as hereinbefore set forth, of the binder-arm, its rock-shaft, the intermittently-actuated binder-gear, the controlling mechanism of the binder-arm, the spring-detent engaging the binder-gear when at rest, the tripping-shaft, its trip-arm, 55 actuated by the binder-gear, and the dog for engaging the binder-arm nose mounted on the tripping-shaft.

90. The combination of the binder-gear and the tripping-shaft actuated thereby, and provided with the yieldingly and fixedly attached dogs, substantially as and for the purpose hereinbefore set forth.

91. The combination of the binder-gear, the tripping-shaft actuated thereby, the spring acting on the tripping-shaft, the dog yieldingly mounted on the tripping-shaft and engaging the binder-arm nose, the fixedly-attached dog of the tripping-shaft, and the stop against which said fixed dog bears, substantially as hereinbefore set forth. 75

92. The combination of the binder-gear, the tripping-shaft, the spring acting on the tripping-shaft, the dog yieldingly mounted on the tripping-shaft and engaging the binder-arm nose, the fixedly-attached dog of the tripping-shaft, the stop-disk, and the rock-shaft on which it is mounted, substantially as and for the purpose hereinbefore set forth. 80

93. The combination of the binding-receptacle, the rocking retainer, compressor, and dis- 85 charger, against which the grain is accumulated as forced into the receptacle, the rock-shaft to which the retainer is fixed, and mechanism for positively actuating the rock-shaft, to compress as well as discharge the bundle, 90 substantially as and for the purpose hereinbefore set forth.

94. The combination, substantially as hereinbefore set forth, of the binding-receptacle, the rocking binder-arm, the vibrating compressor 95 overhanging the grain in the receptacle and actuated by the binder-arm upon its descent, the rocking grain-retainer and gavel-compressor, against which the grain accumulates in the receptacle, the positively-actuated rock-shaft 100 to which the retainer is fixed, and means by which the rock-shaft is operated to cause the compressor to act upon the gavel after the descent of the binder-arm and while the grain is confined by the binder-arm and beneath the 105 vibrating compressor, for the purpose described.

95. The combination of the rocking retainer-arm provided with the side arm at its lower end, the rock-shaft to which it is secured about midway its length, and mechanism for actuating the rock-shaft, substantially as and for the purpose hereinbefore set forth. 110

96. The combination of the rocking grain-retainer, gavel-compressor, and bundle-dis- 115 charger upright arm V^3 , having the curved slotted side arm, V^4 , and the auxiliary pivoted arm jointed to the upright arm and connected with the slot of the side arm, substantially as and for the purpose hereinbefore set forth. 120

97. The combination, substantially as hereinbefore set forth, of the rocking retainer provided with the curved slotted side arm at its lower end, the auxiliary pivoted arm vibrating about its pivotal connection with one end of the retainer and connected at its opposite end with the slotted arm thereof, the rock-shaft to which the retainer is fastened, mechanism for actuating the rock-shaft, and the stop for limiting the movement of the auxiliary arm, for the purpose described. 125

98. The combination of the binder-gear, the rocking retainer, compressor, and discharger, the rock-shaft thereof, the actuating-lever and segment-gear of the rock-shaft, and the pro- 130

jections and sector-gear of the binder-gear acting upon said actuating-lever and segment-gear, substantially as and for the purpose hereinbefore set forth.

5 99. The combination, substantially as hereinbefore set forth, of the binder-gear, the rock-ing retainer, compressor, and discharger, its rock-shaft actuated by the binder-gear, the tripping-shaft, also actuated by the binder-gear, and the arm of the tripping-shaft dogging the rock-shaft.

100. The combination of the spring-actuated tripping-shaft, the fixedly-attached stop-arm thereof, the shouldered disk against which said 15 arm acts, the rock-shaft to which said disk is

fastened, and the binder-gear actuating the rock-shaft and tripping-shaft, substantially as and for the purpose hereinbefore set forth.

101. The combination of the rock-shaft V^2 , the arm V^3 , secured about midway its length thereto, the curved slotted arm V^4 , and the pivoted arm V^5 , having the lateral lug, substantially as and for the purpose hereinbefore set forth.

In testimony whereof I have hereunto subscribed my name.

JOHN S. DAVIS.
